UNITED STATES PATENT OFFICE.

ROBERT F. BOWER, OF DETROIT, MICHIGAN, ASSIGNOR TO BOWER ROLLER BEARING COMPANY, OF DETROIT, MICHIGAN, A CORPORATION OF MICHIGAN.

ROLLER-BEARING CAGE.

Application filed November 14, 1921. Serial No. 514,842.

The invention relates to cages for roller bearings and has for its main object to provide a cage with spacers for the rolls which permit of free lubrication of the rolls and comprise spaced plates engageable with the rolls for relatively short portions of their lengths and cross bars connecting these plates. Other objects of the invention reside in the novel features of construction as more fully hereinafter set forth.

In the drawings:

Figure 1 is an end elevation with parts broken away of a roller bearing unit embodying my invention;

Figure 2 is a side elevation of the parts thereof;

Figure 3 is a longitudinal cross section through a spacer.

1 and 2 are the spaced heads of the roller bearing cage connected by the shouldered tie bars 3 extending therebetween. 4 are the rolls having the reduced pivot portions 5 at their ends extending through apertures in the heads 1 and 2, these apertures being of sufficiently greater diameter than the pivot portions to permit of limited relative movement of the rolls and heads. Each roll has the main cylindrical portion 6 and the enlargement 7 at one end thereof having the oppositely inclined portions 8 and 9 forming bearing surfaces for taking care of end thrusts in opposite directions. The surfaces of the main cylindrical portion and of the inclined bearing portions extend beyond the inner and outer peripheries of the cages and engaging corresponding surfaces in the inner and outer race members 10 and 11 respectively.

To properly space the rolls 4 and to hold the same in parallelism and at the same time to permit of free lubrication of the rolls, there are the spacers 12 which have the end plates 13 extending transversely of the rolls and provided with the concave edges 14 conforming substantially to the curvature of and engaging the main cylindrical portions 6 of the rolls. These end plates have the apertures 15 through which the tie bars 3 pass and are connected by the cross bars 16 extending therebetween and preferably integral therewith, the cross bars being spaced an appreciable distance from the surfaces of the main portions of the rolls, as well as the

tie bars 3, so that lubricant may readily come into engagement with the same. The 55 spacers are positioned longitudinally of the rolls in the present instance by having one end plate adjacent to the head 1 while the other end plate is adjacent to the inner inclined wall of the enlargement. 60

With this arrangement, it is seen that the rolls are spaced by members which may be readily formed as by being stamped out and that these members engage the rolls for only relative short portions of their lengths, the 65 remainder of the lengths of the rolls being exposed to permit of lubricant freely reaching their surfaces.

What I claim as my invention is:

1. In a roller bearing cage, the combination with spaced heads, of tie bars extending therebetween, and spacers for the rolls rotatively secured to said spaced heads, having spacer plates extending transversely of their axes and engageable with relatively 75 short portions thereof, and cross bars spaced from the rolls and secured to said spacer plates for connecting the same.

2. In a roller bearing cage, the combination with spaced heads, of tie bars extending therebetween, and spacers rotatably mounted upon said tie bars and comprising spacer plates extending transversely of the rolls and engageable with the same, and cross bars spaced from the rolls and secured 85 to said plates for connecting the same.

3. In a roller bearing cage, the combination with spaced heads, of tie bars extending therebetween, and spacers for the rolls rotatably mounted upon said tie bars and comprising spacer plates extending transversely of the rolls and engageable therewith, and cross bars spaced from the rolls and integral with said plates.

4. In a roller bearing cage, the combination with spaced heads, of tie bars extending therebetween, rolls extending between said heads intermediate said tie bars and having enlargements, spacers for said rolls mounted upon said tie bars and comprising 100 spacer plates extending transversely of the rolls and engageable with the same near their enlargements and near one of said heads, and cross bars extending longitudinally of and spaced from the rolls and connecting said spacer plates. 105

5. In a roller bearing cage, the combination with spaced heads, of tie bars extending therebetween and spacers mounted on said tie bars comprising a cross member extending longitudinally of said tie bars and integral transversely extending end portions apertured to receive said tie bars, said trans-
- verse end portions being formed with concave bearing surfaces engageable with the rolls and said cross members being spaced from the rolls and from said tie rods.
- In testimony whereof I affix my signature.

ROBERT F. BOWER.
